UNITED STATES PATENT OFFICE

2,439,536

SEPARATOR

Eugene Porter Worthen, Braintree, Fenner Smith Barbour, Wollaston, and Stephen Roger Putnam, North Quincy, Mass., assignors, by mesne assignments, to Buena Vista Iron Company, a corporation of New Jersey

Original application May 27, 1942, Serial No. 444,676. Divided and this application June 7, 1944, Serial No. 539,214

1 Claim. (Cl. 183—111)

1

This invention relates to improvements in purifiers or separators of the internal type employed in boilers and other containers, such as evaporating and distilling apparatus, and the like.

The present application is a divisional application of our copending application Serial No. 444,676, filed May 27, 1942, now Patent No. 2,368,538, January 30, 1945.

The invention relates more particularly to changes and improvements in the separating elements of such a separator and in the general design thereof affecting the discharge and return of the entrained liquids and detritus to its vapor generating source.

We have found that by providing the entrance separating elements with their free discharge direct to the vapor generating source that the largest part of the entrained liquid and particularly of the entrained solid detritus is therein eliminated from the generated vapor, which leaves the interior separating elements free of flooding and therefore more efficient in its final purification of the generated vapor in the passage through the separator. We have also found that it is most important that the advancing flow of saturated vapor through the separator should at no time meet opposed surfaces that would tend to create further atomization of the entrained liquid droplets. To satisfy this condition we have provided entrapping forewalls with thin edges, and we direct the flow at all other points to meet surfaces at a low angle of incidence.

Therefore the main object of our invention is to provide in a separator novel separating elements of high efficiency for effecting entrainment and discharge of liquids containing detritus and dissolved solids from flowing vapor rapidly with respect to their extent and without atomization within the vapor stream.

Other objects and advantages will be apparent from the following description, wherein reference is made to the accompanying drawings illustrating the preferred embodiment of our invention and wherein similar reference numerals designate similar parts throughout the several views.

Figure 1 is a front elevation of the separator unit;

Fig. 2 is a section taken along the lines 2—2 of Figure 1, viewed in the direction of the arrows, and with certain of the division plates removed;

Fig. 3 is a section taken along the lines 3—3 of Figure 2 viewed in the direction of the arrows;

Fig. 4 is a left end side elevation.

2

Referring now to Figures 1 to 4, inclusive, of the drawings, the numeral 10 designates the separator unit comprising a casing 11 preferably made of brass plates brazed together. The casing 11 is a box-like structure comprising the separating compartment 12 and the casing structure 13. The separating compartment 12 is a built-up structure comprising a top plate 14, drain plate 15, side plates 16, front plate 17, splash plate 18, division plates 19, division plates 20, and baffle hooks 21, 22, and 23. The top plate 14 and the drain plate 15 have provided therein a plurality of spaced slots 24 (Figure 2). The division plates 19 and 20 have along their top and bottom edges 15 lugs 25 spaced lengthwise to register with the slots 24. By placing the lugs 25 in their respective slots, and bending them over and brazing them in place, as shown in Figure 3 at 26, the division plates 19 and 20 are held in alternate spaced vertical parallel relation between the top plate 14 and the drain plate 15. The drain plate 15 is also provided with openings 27 along the rear edge for a purpose to be hereinafter described. The baffle hooks 21, 22, and 23 are brazed to the inner sides of the side plates 16 and to both sides of the division plates 19 and 20 in alternate staggered relationship. The baffle hooks 21 are positioned in the inlet opening 28 of the separating compartment 12 and extend vertically between the top plate 14 and the splash plate 18. The inlet opening 28 is preferably in height about two-thirds that of the separating compartment 12. The splash plate 18 is provided with openings 29 in registry with and is brazed at the bottom ends of the baffle hooks 21 for a purpose to be hereinafter described. The front plate 17 is set in from the front edges of the top, drain, and side plates a distance equal to the width of the splash plate 18 for a purpose to be hereinafter described. The baffle hooks 22 and 23 extend between the top plate 14 and the drain plate 15.

It will be noted that the division plates 19 and 20 with side plates 16 form a series of vertical parallel narrow passageways 30 extending from the front to the rear of the separating compartment 12. It will also be noted that the alternate staggered positioning of the baffle hooks between these plates forms a sinuous continuous passageway somewhat as indicated by the dot-and-dash line 3—3 of Figure 2, and that opposed to each turn of the sinuous passageway are forewalls 31 of each of the baffle hooks. The baffle hooks 21 and 22 each have attaching walls 32 while baffle hooks 23 have attaching walls 33 and rear hook

walls 34 and 35. In each case the forewalls are spaced from and joined to the attaching walls by an integral sloping wall 36. The forewalls and attaching walls are parallel to each other and to the division walls and side walls. There is thus formed between the baffle hooks and the walls to which they are attached right trapezium-shaped pockets 37 having their acute angled end closed. The slope of the walls 36 with respect to the division walls and side walls, to which they are respectively attached, is preferably of the order of approximately one-third of a right-angle for a purpose to be described hereinafter. The top ends of the hook baffles 22 and 23 rest against the top plate 14, while their lower ends rest upon the drain plate 15, whereby the pockets 37 and 38 formed by the walls 31 and 36 and walls 34 and 35, respectively, are open only along their front right-angled vertical face. The pockets 39 formed by the walls 31 and 36 of the hook baffles 21 are likewise open along their front right-angled vertical face, and by reason of the openings 29 in the splash plate 18 are open at their lower ends. It will be noted that the preferred narrowwise width of the pockets 37 and 38 is approximately that of one-half of the width of space between adjacent division walls, and that the open width of the pockets 39 is approximately that of the width of space between adjacent division walls, whereby the respective forewalls are practically in line along the centerline between any two division walls. The significance of the specific design of the baffle hooks 21, 22, and 23 and their relation to adjacent elements will be more fully described hereinafter.

The casing structure 13 is a built-up structure and forms a mounting for the separating compartment 12 and in conjunction therewith establishes a settling chamber 40 within the separating compartment 12, and a drain pot chamber 41 just below the separating compartment 12. The casing structure 13 comprises case side plates 42, back plate 43, bottom plate 44, drain pot front plate 45, baffle flange 46, case front lower flange 47, case front side flanges 48, case front top flange 49, top attaching flange 50, side attaching flanges 51, supports 52, lower attaching flanges 53, and drain pipe bosses 54. The case side plates 42, together with flanges 47, 48, and 49 re-enforced by the flanges 50, 51 and front plate 45 form a frame within which, when the separating compartment 12 and the casing structure 13 are assembled together, the front end of the separating compartment 12 is supported. When thus assembled the rear end of the separating compartment 12 is supported upon the bottom plate 44 through the intermediary supports 52.

The drain pot chamber 41 is enclosed by the case side plates 42, back plate 43, bottom plate 44, and drain pot front plate 45 of the casing structure 13, and by the drain plate 15 of the separating compartment 12. The rear of the settling chamber 40 is communicated with the rear of the drain pot chamber 41 by way of the openings 27 in the rear edge of the drain plate 15, and by way of a dished channel 55 formed in the back plate 43. Bolt holes 56 in the attaching flanges 50, 51, and 53, and in back plate 43 provide means for mounting the separator unit 19 in its operating position. The back plate 43 closes off the lower portion of the rear of the separating compartment 12 thereby leaving a vapor outlet opening 57 of preferably the same height as the inlet opening 28, and also acts as the rear closing wall of the settling chamber 40. 70

We will now describe the operation of our improved separator.

As already set forth hereinbefore we have provided in our separator a large number of separating elements mounted upon vertical division walls in such a manner that vapor passing through the separator from its inlet to its outlet is forced to travel in comparatively thin vertical streams between the division walls and by reason of the staggered positioning of the separating elements the thin vertical streams are constrained to travel a gently sinuous path of shallow corrugated cross-section. This sinuous path is further characterized in that by reason of the length of the forewalls 31, of the sloping walls 36, and of the length of division wall between each successive baffle hook the sinuous path is one broadly of a succession of short straight sections of flow alternately parallel to and sloped to the through-flow line. 15 These short straight sections of flow are important since they tend to project the entrained droplets and detritus quickly into the pockets from forward parallel flow and from the sloping flow the droplets are projected against the walls at a low angle of incidence so that atomization is minimized and the water attaches itself as a film to the wall surfaces and under the influence of the vapor flow is forced into the angle of the trapezium-shaped pockets where, the vapor flow being neutralized, the gathered liquid flows downward by force of gravity. It will also be noted that the advancing flow of saturated vapor through the separator at no time meets opposed surfaces to create atomization of the water droplets. Only the thin edges of the forewalls are opposed at a normal angle, the flow at all other points meets surfaces at a low angle of incidence. It should also be noted that the angle at which the outer surface of the baffle hooks change is so gradual that the water film thereon is not blown off to re-enter the vapor stream but adheres as a film on the walls until gathered in the neutral angles of the pockets.

Our separator is also characterized by plural qualitative drains. As hereinbefore set forth the entrance baffle hooks 21 set off pockets 39 which are adapted to discharge from their bottom ends through openings in the splash plate 18 directly downward. The remaining interior separating elements as hereinbefore set forth, are adapted to drain from their bottom ends onto a drain plate, and discharge from the rear of the drain plate into a drain pot and thence downward by pipe. Another feature, also hereinbefore set forth, is in setting off a lower third of the interior separating elements by means of front and rear walls to form a settling chamber of neutralized vapor flow to facilitate the drainage of the liquid entrained therein.

These features of plural qualitative drainage are very important and are the result of considerable experimentation and development work. We have found that in the usual design of separators with a single discharge means the greater proportion of entrained liquid and detritus extracted occurs in the first line of separating elements and that the flooding of these first separating elements detracts from the efficiency of the succeeding separating elements and from the efficiency of the separator as a whole. By assuring rapid and thorough drainage of the first line of separating elements the remaining ones are more effective in purifying the vapor stream. Furthermore, drainage of the latter separating elements and the thoroughness of purification was

found advanced by the provision of the settling chamber protected from the passing vapor stream and by having its liquid discharge only at the rear thereof. This latter arrangement was found to preclude picking up and carrying onward to the condensers moisture from the last rows of separating elements due to circulating currents of vapor.

Although we have described and illustrated our invention in considerable detail, we do not wish to be limited to the exact and specific details thereof as shown and described, but may use such modifications in, substitutions for, or equivalent thereof, as are embraced within the scope of our invention, or as are pointed out in the claim.

Having thus described our invention, what we claim as new and desire to secure by Letters Patent is:

A vapor separator unit comprising a casing having a top wall, side walls, and a bottom drain plate and vertical division walls defining a plurality of narrow conduits each having a vapor inlet front end and a vapor discharge rear end, each said conduit comprising a plurality of comparatively narrow flat liquid-intercepting forewalls disposed in spaced vertical flat-wise approximate alignment with the center-line plane of said conduit, each of said forewalls having an unattached front edge directed toward said vapor inlet front end, the rear edges of each of said forewalls being attached alternately to opposed adjacent division walls by a connecting wall forming an angle with either face of its respec-

tive forewall greater than a right angle, having a low angle of incidence to said division walls whereby liquid-intercepting pockets are formed vertically on said conduit walls, individual drain means for each first one of said pockets for discharging liquid entrained therein, and collective drain means for all remaining of said pockets for discharging separately the liquid entrained therein, said collective drain means comprising front and rear walls forming a settling chamber enclosing the lower ends of said remaining of said pockets, drainage openings along the rear edge of said drain plate, and a drain pot adapted to receive the entrained liquid from said settling chamber and to discharge it therefrom.

Certificate of Correction

Patent No. 2,439,536.

April 13, 1948.

EUGENE PORTER WORTHEN ET AL.

It is hereby certified that error appears in the printed specification of the above numbered patent requiring correction as follows: Column 6, lines 1 and 2, strike out "having a low angle of incidence to said division walls"; and that the said Letters Patent should be read with this correction therein that the same may conform to the record of the case in the Patent Office.

Signed and sealed this 8th day of June, A. D. 1948.
